UNITED STATES PATENT OFFICE.

WILLIAM S. PRITCHARD, OF DETROIT, MICHIGAN, ASSIGNOR TO MOTOR PRODUCTS CORPORATION, OF DETROIT, MICHIGAN, A CORPORATION OF NEW YORK.

TUBE-CUTTING MECHANISM.

1,424,179.

Specification of Letters Patent. Patented Aug. 1, 1922.

Application filed October 27, 1919. Serial No. 333,796.

To all whom it may concern:

Be it known that I, WILLIAM S. PRITCHARD, a citizen of the United States of America, residing at Detroit, in the county of Wayne and State of Michigan, have invented certain new and useful Improvements in Tube-Cutting Mechanism, of which the following is a specification, reference being had therein to the accompanying drawings.

10 The invention relates to the manufacture of tubing and it is particularly applicable to the method of manufacture in which long strips of metallic ribbon are fed through a tube forming machine and are continuously advanced during the performance of the several operations incident to the completing of the tube. The main object of the present invention is to provide a mechanical construction for successively severing the continuously advancing tube into sections of a predetermined length. Another object is the provision of means for preventing the distortion of the tube being cut when its length is relatively great. Other objects of 25 the invention reside in the novel arrangements and combinations of parts as more fully hereinafter set forth.

In the drawings:

Figure 1 is a plan view of the machine embodying my invention;

Figure 2 is a perspective view of a portion thereof;

Figure 3 is a cross section on the line 3—3 of Figure 1;

Figure 4 is a cross section on the line 4—4 of Figure 1;

Figure 5 is a cross section taken at right angles to Figure 4;

Figures 6, 7, 7^a, 8 and 9 illustrate modified constructions of different details.

The tube is delivered from a tube forming mechanism (not shown), and since it is continuously advancing it is necessary that the severing operation should be performed without interference with such advancement. It is also necessary that the severed sections be of an exact predetermined length. To accomplish this, I have provided a mechanical construction which is actuated by the advancing end of the tube for moving the severing device in the same direction and at the same speed as the tube is advancing during the interval in which the severing device is performing its operation.

55 1 is a saw for severing the tube, this saw

being mounted upon an arbor 2 which is slidably mounted in bearings 3. 4 is a rotary driving means for the arbor 2, such as an electric motor which is coupled to the arbor by a telescopic connection 5 permitting 60 of independent longitudinal movement. As shown, this telescopic connection comprises a head 6 secured upon the arbor and driven from the motor by means of the parallel pins 6' slidably engaging the head. The arbor is 65 moved longitudinally by the pressure of the advancing tube, and the mechanism for accomplishing this result is as follows: 7 and 8 are collars on the arbor 2 and secured thereto by suitable means, such as set screws 70 9. Between these collars is arranged a sleeve 10 having the lateral arm 11 which carries the gauge member 12. The latter includes a flaring mouth piece 13 for receiving the advancing end of the tube and guiding 75 the same against a plunger 14 within the gauge member, which in turn engages the stop plate 15, through which motion is communicated to the arm 11, sleeve 10, collars 7 and 8 and arbor 2. Thus, as soon as the 80 end of the tube engages the plunger 14 and forces the latter into contact with the plate 15, the arbor 2, and saw 1 carried by the arbor, will travel at the same speed as the tube and in the same direction, so that the 85 tube may be severed without interfering with its advancement.

To sever the tube it must be moved laterally into the saw, and as soon as the section is severed the main portion of the tube must 90 be quickly removed from the path of the saw so that it can continue its advance while the saw and arbor are being returned to their initial positions. This lateral movement I accomplish by a mechanical construction which is operated by means of the advancing tube. As shown, 16 is a guide into which the tube enters when it leaves the tube forming mechanism (not shown). 17 is a second guide pivotally connected at one end 95 18 to the first-mentioned guide, and at the opposite end 19 to the flaring mouth piece 13. 20 is a rock arm pivotally mounted at 21 in the stationary member 22 upon the machine and having the cam bearing 23, 100 which is adapted to engage the guide 16 upon rocking of the rock arm 20 to force the guide 16 laterally toward the saw 1 a sufficient distance to permit the saw to sever the tube passing through the guide 16. 24 110

is a tie rod pivotally connected to the rock arm 20 and extending substantially parallel to the guides 16 and 17, the opposite end of the tie rod preferably having a flattened portion 25. By pulling this tie rod 24 the rock arm 20 will be rocked thereby laterally swinging the guide 16 and also the second guide 17 by means of the cammed portion 23 upon the rock arm.

10 For the purpose of gripping the tie rod 24 to pull the same, the following construction is provided. The plunger 14 which is adapted to be engaged by the advancing end of the tube is provided with the beveled shoulder 26 on the side toward the tie rod, which is adapted to slidably engage the rod 27 extending transversely of the plunger to force the rod 27 outward to engage the flattened portion 25 of the tie rod and clamp 20 the tie rod against the housing 28 through which the tie rod passes, and which is secured to the lateral arm 11 upon the sleeve 10. As the tube advances it will also advance the tie rod 24 at the same speed which, 25 as above described, swings the tube into engagement with the saw 1 to be severed thereby.

After the tube has been severed, it is essential that the guides 16 and 17 be returned to their initial positions, which is accomplished by the following construction. 29 is a coil spring located between the inner end of the plunger 14 and the stop plate 15 for returning the plunger 14 to its initial position. 30 35 is a coil spring located between one end of the slot 31 in the cover 32 of the housing 28, and the block 33 also located in the slot and connected to the rod 27 by means of the pin 34, the arrangement being such that, as 40 soon as the plunger 14 is returned to its initial position, the rod 27 will be returned to its initial position by means of the coil spring 30 through the block 33 and its pin 34, thereby releasing the tie rod 24. 35 is a 45 spring coiled around the rod 36 and located between the stationary arm 22 of the machine and the nut 37 threaded upon the outer end of the rod 36, the inner end of this rod being pivotally connected to the guide 16, as 50 at 38, and preferably extending through the stationary arm 22. This coil spring 35 laterally swings the guide 16 to its initial position thereby swinging the second guide 17 and also the rock arm, or cam member, 20 55 to their initial positions.

For returning all the parts of the machine which move with the tube to their initial positions, the coil spring 39 is provided coiled around the arbor 2 and located between the rear bearing 3 and the collar 40 upon the arbor 2 and secured thereto, as by the set screws 41.

For opposing a yieldable resistance to the forward movement of the parts there is provided the following construction in which

42 is a latch housing secured at the side of the sleeve 10 within which is mounted the spring pressed latch 43 having its lower end 44 beveled to permit of the housing 42 and sleeve 10 advancing with the tube, the beveled portion sliding up over the beveled side 45 of the notch 46 located in the block 47. The friction between the latch and the block tends to retard the forward movement of the parts. Upon the return of the sleeve 10 and latch housing 42, the end of the latch 43 engages in the notch 46.

In order to secure different predetermined accurate lengths of the severed sections of the tube, the collars 7 and 8 are adjustable longitudinally of the arbor 2 and are secured in fixed position thereon by the set screws 9. Different predetermined lengths of the second guide 17 are provided, the correct one of which being substituted in the machine. Furthermore, the block 47 is adjustable, the adjustment being permitted by means of the slots 49 in the block, which are engaged in by the bolts 48. The flattened end portion of the tie rod 24 extends through the housing 28 a sufficient distance to permit of the desired variation in lengths of the severed sections.

In operation the parts are normally in the position shown in Figure 1, where the arbor 2 is in its retracted or initial position, being yieldably held in this position by the spring 39. Whenever the machine is in operation the formed tube will be continuously delivered from the tube forming mechanism (not shown) into the laterally movable guides 16 and 17, and the forward end of the advancing tube, after passing through these guides enters the flaring mouth piece 13 and engages the plunger 14 which, through the transversely extending rod 27, clamps the tie rod 24 against the housing 28. The plunger also engages the stop plate 15 to move it in the same direction and at the same speed as the tube is advancing, the housing 28, thereby laterally swinging the guide 16 toward the saw 1 to sever the tube, and the arm 11 upon the sleeve 10, thereby moving the arbor 2, upon which the saw 1 is mounted, so that it is seen that the tube is laterally swung into engagement with the saw 1 and the latter travels with the tube so that it does not affect the continuous advancement of the tube.

Also since the guide 16 is connected to the gauge member 12 through the second guide 17, the former guide will be advanced with the tube, thereby maintaining its forward end constantly in proximity to the saw 1 while the latter is in operation. This saw 125 enters a space between the adjacent ends of the guides 16 and 17 sufficient to completely sever the tube passing therethrough. As soon as the section of the tube is severed it will be moved out of the path of the follow- 130

ing tube by the rotary movement of the saw and the parts will all assume their initial or retracted positions as previously described.

As shown in the modified construction in Figure 6, the coupling connection between the motor 4 and the arbor 2 comprises the parallel rods 50 on opposite side of the axis of the motor and engaging bearings in the head 51 which is secured to the arbor 52 of the saw. This arbor is hollow and is provided with the cross pin 53. Located inside this arbor, and abutting against the cross pin 53 is the retracting coil spring 54 for moving the saw 1 and other parts to their initial or retracted positions. The opposite end of the coil spring abuts against the plunger 55, which extends between the parallel rods 50 and has a bearing upon the head 56 connected to the motor shaft and to which the parallel rods 50 are also connected. The length of the plunger 55 is adjustable to vary the tension of the spring 54 this adjustment comprising the threaded member 57 engaging in the plunger 55 and locked in its adjusted position by means of the lock nut 58.

Figure 7 discloses a modified construction for clamping the tie rod 24. Specifically, 59 is a member extending transversely of the gauge member 12 and secured to the lateral arm 11 of the sleeve 10, this transversely-extending member having the rounding bearing 60 for engaging the upper portion of the tie rod 24. 61 is a cooperating member pivotally mounted at 62 near its outer end and having the rounded bearing 63 in its upper surface for engaging the lower portion of the tie rod 24, the tie rod extending through between the cooperating 40 members. The plunger 64 in the flaring mouth piece 13 has the beveled shoulder 65 for engaging a shoulder 66 at the inner end of the cooperating member 61 and rocking the inner end downward thereby clamping the bearing 63 at the outer end of the cooperating bar against the tie rod 24 thereby securing the tie rod between bars 59 and 61.

As shown in Figure 8, the coil spring 67 for returning the guide 16 to its initial 50 position is on the side of the guide 16 opposite to that of the rock arm 20, this coil spring is located between the plunger 68 which engages the guide 16, and an adjustment screw 69 threadingly engaged in the stationary arm 22.

Figure 9 shows the coil spring 70 for returning the guide 16 to its initial position, as encased in the housing 71, the arrangement of parts otherwise being substantially the same as disclosed in Figure 1.

The lengths of the severed sections of the tube will be predeterminedly varied, and for each length of section a different length of second guide 17 is used. For the longer 65 lengths of severed sections it is essential

that the tube be guided on all sides while it is initially engaging the plunger 14 and advancing the movable parts of the severing mechanism in order to prevent distortion of the tube. This is accomplished by the following construction: The guide 17 comprises the box 72 and the box cover 73 hinged to the box as at 74. 75 and 76 are respectively upper and lower cooperating cam members, these members being stationary and being provided in their adjacent faces with the grooves 77 and 78 respectively. 79 is a cam ball engageable in the grooves 77 and 78 and mounted upon the arm 80 which is secured to the cover 73 of the guide. In the initial or retracted position of the guide 17 the cam ball 79 is in the lower portions of the grooves 77 and 78, as shown in Figure 4 particularly, and the cover 73 is closed so that the tube is enclosed. As the tube advances, it engages the plunger 14 and through this plunger advances the moving parts of the severing mechanism including the guide 17. The forward movement of the guide advances the arm 80 and the cam ball 79 to bring the latter into engagement with the upwardly inclined portions of the grooves 77 and 78, thereby swinging the cover 73 of the box 72 into open position to permit of the removal of the tube after it has been severed. The upwardly inclined portions of the grooves 77 and 78 are positioned so that the cover is opened prior to the complete severing of the tube. However, the tube is held in position by the flaring mouthpiece 13 at one end and by the guide 16, so that it cannot drop out of the guide 17, until completely severed. After the tube section has been severed the parts are returned to their initial positions when the cover 73 swings to closed position and the guide is ready to receive another length of tube.

What I claim as my invention is:

1. In a mechanism for cutting continuously moving tubing, the combination with a laterally movable guide through which the tubing is delivered, of a rotary severing device having a fixed axis of rotation, a gauge located in advance of said severing device, a member carried by said gauge and actuated by the forward end of the advancing tubing, and a second member for moving said guide laterally across the path of the severing device, said second member being actuated from said gauge and its movements being controlled by said first mentioned member.

2. In a mechanism for cutting continuously moving tubing, the combination with a rotary severing device having a fixed axis of rotation of a guide for the tube movable across the path of travel of said moving device, a cam member for moving said guide across the path of travel of said severing device a gauge adjustably connected to said

severing device in advance thereof, a member carried by said gauge and having a limited movement relative thereto, said member being adapted to be actuated by the forward end of the tube, and means controlled by said member for actuating said cam member.

3. In a mechanism for cutting continuously moving tubing, the combination with a device for severing the tubing, of a guide 10 for the tube movable across the path of said severing device, a member for moving said guide across the path of said severing device, and means actuated by the tube itself for operating said member and for moving 15 said guide and severing device with the tube.

4. In a mechanism for cutting continuously moving tubing, the combination with a device for severing the tube, of a guide 20 for the tube movable across the path of said severing device, a cam member for moving said guide, a rod secured to said cam member, a plunger adapted to be actuated by the forward end of the tube, a member 25 adapted to be moved with said plunger, and a second member adapted to be actuated by said plunger and co-operating with said first mentioned member to clamp said rod.

5. In a mechanism for cutting constantly moving tubing, the combination with a 30 device for severing the tube, of a guide for the tube movable across the path of said severing device, a cam member for moving said guide, a rod secured to said cam member, a gauge adapted to be set a predetermined distance in advance of said severing 35 device, a plunger carried by said gauge and adapted to be actuated by the forward end of the tube, a member through which said rod extends and adapted to be moved by 40 said plunger in its direction of movement, and a second member adapted to be moved transversely of said plunger and by said plunger, said second member co-operating with said first mentioned member to clamp 45 said rod.

6. In a mechanism for cutting continuously moving tubing, the combination with a laterally movable guide through which the tubing is advancing, a rotary severing device, a longitudinally movable arbor carrying said severing device, a gauge adapted to be connected to said arbor at a predetermined distance in advance of said severing device, means adapted to be connected to said 50 guide for laterally moving the same, means carried by said gauge and adapted to be actuated by the forward end of the tube for connecting said guide, and first mentioned means, means for returning said arbor to its 55 initial position after the tube has been severed, and a latch member connected to said arbor for limiting the return movement.

7. In a mechanism for cutting continu-

ously moving tubing, the combination with 65 a guide through which the tubing is advancing, of a rotary severing device, means operated by the forward end of the advancing tubing for relatively moving said guide and severing device toward each other, said 70 means moving said severing device in the same direction and at the same speed as the tubing is advancing, and means for enclosing the portion of the tubing between said severing device and its forward end during 75 its initial engagement with said moving means.

8. In a mechanism for cutting continuously moving tubing, the combination with a laterally movable guide through which the 80 tubing is advancing, a rotary severing device having a fixed axis of rotation, a gauge adapted to be set a predetermined distance in advance of said guide, a sectional guide for the tubing pivotally connected to said gauge and first-mentioned guide at its ends, means for laterally moving said first-mentioned guide, means carried by said gauge and adapted to be actuated by the forward 85 end of the tubing for controlling and operating said first-mentioned means, and means for holding the sections of said sectional guide closed during the initial engagement of the tube with said means carried by the gauge.

9. In a mechanism for cutting continuously moving tubing, the combination with a laterally movable guide through which the tubing is advancing, of a rotary severing device having a fixed axis of rotation, a member 90 for moving said guide laterally across the path of said severing device, clamping means located in advance of said severing device and adapted to be actuated by the forward end of the advancing tubing, and an actuating connection for said guide moving member adapted to be operated by said clamping means.

10. In a mechanism for cutting continuously moving tubing, the combination with a device for severing the tube, of a sectional 110 guide for the tube movable toward said severing device to move the tube across the path of said severing device, means adapted to be actuated by the tube itself for moving said sectional guide toward said severing device and for moving said sectional guide and severing device with the tube, and means for maintaining the sections of said guide together during the initial engagement of the tube with said moving means and for subsequently separating the sections of said guide to permit removal of the severed sections of the tube.

In testimony whereof I affix my signature.

WILLIAM S. PRITCHARD.
